(57) **CLAIM**

The ornamental design for a lampholder, as shown and described.

DESCRIPTION

FIG. 1 is a top, front, right side perspective view of a lampholder, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion 9 in FIG. 1;

FIG. 10 is an enlarged view of the portion 10 in FIG. 1;

FIG. 11 is an enlarged view of the portion 11 in FIG. 3; and,

FIG. 12 is an enlarged top view of a lampholder.

The evenly dashed broken lines illustrate portions of the lampholder and form no part of the claimed design. The unevenly dashed broken lines define the boundaries of enlarged views and form no part of the claimed design.
